[57] CLAIM

The ornamental design for a video display for a vehicle, as shown and described.

DESCRIPTION

FIG. 1 is a front elevational view of a video display for a vehicle showing our new design, with the broken lines shown for illustrative purposes only and forming no part of the claimed design;

FIG. 2 is a rear elevational view thereof;

FIG. 3 is a left-side elevational view thereof;

FIG. 4 is a left side elevational view thereof, with the display portion shown in an elevated position;

FIG. 5 is a right-side elevational view thereof; and,

FIG. 6 is a top plan view thereof, with the bottom being plain and unornamented.

FIG. 2

FIG. 1

FIG. 3

FIG. 4

FIG. 5

FIG. 6
